OTHER PUBLICATIONS

Product literature for Flettner '2000.' Date unknown. Four (4) sheets.

(List continued on next page.)

Primary Examiner—Louis S. Zarfas

Assistant Examiner—Robert A. Delehanty

(74) Attorney, Agent, or Firm—Clayton, Howarth & Cannon, P.C.

(57) **CLAIM**

We claim the ornamental design for a ventilation cover, as shown and described.

DESCRIPTION

FIG. 1 is a top perspective view thereof;
FIG. 2 is a bottom perspective view thereof;
FIG. 3 is a first side view thereof;
FIG. 4 is a second side view thereof;
FIG. 5 is a front side view thereof;
FIG. 6 is a rear side view thereof;
FIG. 7 is a top plan view thereof; and,
FIG. 8 is a bottom plan view thereof.**1 Claim, 8 Drawing Sheets****OTHER PUBLICATIONS**
